UNITED STATES PATENT OFFICE

EUGENE SCHUCK, OF LOS ANGELES, CALIFORNIA, ASSIGNOR OF ONE-FOURTH TO GEORGE E. MCCREERY, OF LOS ANGELES, CALIFORNIA

MANUFACTURE OF SOAP

No Drawing.

Application filed March 19, 1930. Serial No. 437,273.

This invention relates to an improved method for the manufacture of soaps of high soap content and low water content and which are moreover stable and durable.

5 The ordinary methods of soap manufacture result in the production of soap of high water content. In order to produce soap of high soap and low water content, the soap of high water content has been subjected to a drying operation. In general, two methods of procedure have been followed in making soap of high soap content and low water content. According to one method, the fatty material is saponified in large kettles, with boiling and final settling of the soap, which is then run over cooling rolls, shredded and dried in a suitable dryer. According to the other and older method, the hot soap from the soap kettle is cooled in frames, 15 cut into slabs and bars, shredded with the so-called "chipper", and placed on drying screens to be dried, either by letting it stay on these screens long enough or by putting the screens into a drying chamber. Soap 20 can be produced according to these and other methods of manufacture which contains a high percentage of soap and a low water content, but they involve expensive drying and other operations, as well as costly machinery, 25 and they consume a great deal of time.

The present invention provides an improved method in which such objectionable drying and other operations are eliminated or greatly simplified, and in which a soap of 30 high soap content is directly produced in a simple and advantageous manner.

I have found that if glycerides of animal or vegetable origin and containing a varying percentage of free fatty acids are intimately 35 mixed with a limited amount of water, sufficient to dissolve the caustic alkali employed, and finely pulverized caustic soda or potash then admixed under conditions described below, or if the glycerides are intimately mixed 40 with a hot freshly formed solution of caustic alkali dissolved in a minimum amount of water, an emulsion is formed in the mixer which undergoes in a short space of time a process of spontaneous generation of heat so great that 45 it produces an intimate and substantially

complete saponification. I have found that soaps can be thus produced which are perfectly saponified and do not contain more than 0.025% free caustic alkali, the saponification being more complete than that obtained with either the boiled or the so-called cold and semi-boiled processes of soap manufacture. The soap is moreover, directly produced with a low water content and high soap content so that further drying is unnecessary.

55 The following more detailed description will further illustrate the process of the invention:

A suitable quantity of animal fat or vegetable oil is placed in a mixer with revolving screw or paddle arrangement for bringing about intimate mixture of the fatty material and added ingredients. The temperature of the fatty material may range between about 100 and 150° F. According to the saponification number of the fatty material, powdered caustic soda of 76% sodium oxide (Na_2O) is 60 carefully weighed and prepared for adding to the mixer. One part of such caustic soda can be dissolved in about 0.4 to 0.7 parts of water, thereby forming solutions of caustic alkali having concentrations of about 70 per cent and 58 per cent respectively. A sufficient quantity of water for dissolving the weighed amount of caustic soda is added 65 to and intimately mixed with the fatty material in the mixer. Then the powdered caustic soda is slowly added under constant agitation or admixture until the mass presents a uniform emulsified appearance. Caustic alkali and water may be used in any ratio 70 not less than one. An aqueous caustic alkali solution is saturated at ordinary room temperatures when equal parts of water and alkali are employed. The use of alkali solutions having concentrations lower than 50 per cent involves the introduction of excess water which of course is one factor found 75 in ordinary soap manufacture which is avoided in my novel process.

80 This emulsified mass is withdrawn from the mixer as soon as it begins to thicken and is collected in a suitable receiving tank. In a few minutes, a self-heating process takes 85 place. The mass develops such an intense 90

heat that its temperature rises, e. g. to around 300 to 320° F., with formation of steam and raising of the mass in the container. This generation of heat and accompanying saponification process continues, according to the size of the batch, for a period of several minutes, e. g. around 8 to 10 minutes, more or less, after which the newly formed soap settles back in the container. After standing 10 for a further period of time, for example, around 25 to 30 minutes, the saponification reaction is substantially completed, and the hot liquid soap can then be removed from the container and cooled, for example, by 15 passing it between revolving water cooled iron rolls, revolving against each other, on which it is cooled and solidified, and from which it can be scraped off or peeled off by knives closely set against the rolls. The soap 20 is thus directly produced in a flaked or shredded form and may be either packed immediately as soap chips, or it may be pulverized and formed into powdered or granulated soap, or it may be further treated, for example, by passing it through a plodding machine to form milled toilet soap.

By using a limited amount of water, sufficient to dissolve the powdered caustic soda, and mixing it with the fat before the caustic 30 soda is added, the caustic soda, when added, dissolves in water which is distributed through the fat, forming a saturated or nearly saturated solution of caustic soda in the water which solution then acts upon the fat 35 to bring about rapid and complete saponification. Owing to the limited amount of water employed, there is no large amount of water to be removed. Some of the water 40 may be removed as steam during the saponification, as a result of the high temperatures attained. The entire operation requires only a comparatively short period of time, and simple and inexpensive equipment. The saponification is carried to substantial completion 45 and the soap is produced directly in a dry state, with a low water content and a high soap content, and the soap, when produced, is ready for market or for packaging, or for further treatment, e. g. in making 50 milled soap.

The process will be further illustrated by the following specific examples. The parts are by weight:

Example 1.—300 parts of corn oil of saponification number about 190 are put into a mixer. There is added and intimately admixed with the oil an amount of water which, together with that contained in the powdered caustic soda, will be sufficient for 55 dissolving the caustic soda. The amount of water is in the neighborhood of 16.3 parts (in addition to that in the caustic soda), and the amount of caustic soda required for saponification is about 40.7 parts. If the 60 caustic soda is employed as 76% caustic con-

taining 24% moisture, this moisture should be allowed for and only sufficiently additional water added to permit dissolving of the entire amount of caustic soda. The water is added to the mixer and intimately 70 admixed with the oil by rotation of the paddles, then the caustic soda is introduced gradually under constant agitation and the mixing is continued until the contents of the mixer presents a homogeneous emulsion 75 which begins to thicken gradually.

As soon as the emulsion, on rotation of the stirrers, becomes streaky, the mixture is discharged from the mixer into a suitable container where the reaction will proceed 80 and the emulsion will gradually begin and develop a great deal of heat, so much, in fact, that during the saponification or self-heating process, the newly formed soap reaches a temperature above the boiling point of water 85 and rises considerably in the container. After a certain time, the self-heating process stops and the soap recedes in the container. At this stage it may be shredded between 90 water cooled iron rolls against which a shredding knife is closely set, and the shredded soap can then be packaged for shipment.

Theoretically, the soap made according to the above example would have approximately the following composition, expressed in terms of the ingredients employed:

	Parts
Glycerides (corn oil)	300
Sodium oxide (Na ₂ O)	30.93
Water	100
	356.99

The theoretical moisture content of a soap produced from these ingredients would be about 7.2%, but in practice it is somewhat less because of the self-heating and resulting evaporation of moisture during saponification.

Example 2.—300 parts of cocoanut oil are treated in a manner similar to that described in Example 1, except for the change in the amount of caustic soda required for the saponification, and the corresponding adjustment of the amount of water used.

It is also possible to replace part of the caustic soda with caustic potash in order to produce a product which will mill more smoothly and have a finer texture. It is also possible, and in some cases desirable, that the smallest dissolving ratio of water be used in dissolving the caustic soda before the mixing, that is, about 0.4 parts of water for 1 part of caustic soda, in which case the admixture will be of the caustic soda solution with the glycerides. A solution of caustic alkali of alkali-water ratio of 1:0.4 may be obtained by taking advantage of the heat of solution of caustic alkali or by dissolving the alkali with the aid of heat. Such a solution is su-

persaturated with respect to ordinary room temperature.

It will thus be seen that the present invention provides a simple and rapid method of forming soaps of high soap and low water content in cake, chip or powder form, from fatty glycerides in which the ingredients can be mixed cold, and the reaction carried rapidly to completion with self-heating by the heat of saponification. It will further be seen that the process results directly in the production of completely saponified and relatively dry soap from low titre glycerides, with only a low or minimum moisture content, which can be directly converted into a merchantable form, for example, by rapid chilling on cooling rolls. Such soaps are firm, durable, less subject to hydrolysis and therefore not as likely to 20 turn rancid as soaps of high moisture content made by the common methods of manufacture above referred to.

The process presents many advantages, giving a marketable soap in a short period of time, with saving of time, machinery, labor, heat, factory space, etc.

Different glycerides can be used for making soaps according to the present process, and such glycerides may contain varying percentages of free fatty acid. The process can also be varied in the amounts and proportions of the ingredients employed without departing from the spirit and scope of the invention.

35 I claim:

1. A process for the manufacture of soap with caustic alkali, which comprises admixing with the fatty materials a given weight of caustic alkali and a limited amount of 40 water weighing not more than the weight of said caustic alkali, emulsifying the resulting mixture, and causing the saponification to take place under self-generation of heat to produce directly a finished soap of low water content.

2. A process for the manufacture of soap, which comprises forming a supersaturated solution of caustic soda by dissolving dry caustic soda in substantially the minimum 50 amount of water required for its dissolution, admixing the resulting hot freshly prepared solution with the proper amount of fatty material to effect saponification, and thereby causing the saponification to take place with 55 substantial completeness and under self-generation of heat to produce directly a finished soap product of low water content.

3. A process for the manufacture of soap, which comprises admixing with the fatty materials a given weight of caustic alkali and a limited amount of water weighing not more than the weight of said caustic alkali, and bringing about intimate admixture thereof with the fatty material, and causing the 65 saponification to take place under self-gener-

ation of heat to produce directly a finished soap product of low water content.

4. A process for the manufacture of soap in chip or powdered form, which comprises subjecting fatty glycerides to saponification 70 with a hot saturated aqueous solution of caustic alkali under self-generation of heat to produce a finished soap product of low water content in a hot molten state, and directly cooling such molten product and converting the same into a chip or powdered form ready for packaging.

In testimony whereof I affix my signature.
EUGENE SCHUCK.
